UNITED STATES PATENT OFFICE.

LEO MORSE, OF NEW YORK, N. Y.

DESIGN FOR A FIGURE TOY.

55,810.

Specification for Design.

Patented July 13, 1920.

Application filed January 19, 1920. Serial No. 352,630. Term of patent 7 years.

To all whom it may concern:

Be it known that I, LEO MORSE, a citizen of the United States, and a resident of the city of New York, in the county and State of New York, have invented a new, original, and ornamental Design for a Figure Toy, of which the following is a specification, reference being had to the accompanying drawing, forming part thereof.

The figure is a front perspective view of a figure toy, showing my new design.

I claim:

The ornamental design for a figure toy, as shown.

LEO MORSE.
